UNITED STATES PATENT OFFICE.

RICHARD W. SAGE AND HARRY R. BOUGHNER, OF AUGUSTA, KANSAS.

SAND-REEL-OPERATING MECHANISM.

Application filed October 11, 1923. Serial No. 667,931.

To all whom it may concern:

Be it known that we, RICHARD W. SAGE and HARRY R. BOUGHNER, citizens of the United States of America; residing at 5 Augusta, county of Butler, and State of Kansas, have invented new and useful Improvements in Sand-Reel-Operating Mechanism, of which the following is a specification.

10 This application is a continuation in part of application Serial No. 485,438, filed July 18, 1921, for drilling rig sand reel.

This invention relates to oil well drilling rigs and particularly to sand reels for operating bailers, or pulling rods and the like.

Prior to our invention, sand reels have been used with standard drill rigs and while the sand reels worked more or less successfully there were certain objections to their 20 construction and operation which impaired the efficiency of the mechanism.

For example, oil drilling rigs are of standard construction and have employed substantially the same mechanism since the 25 beginning of the oil industry, so any successful sand reel must of necessity be so constructed that it can be driven from a working part of the standard rig. The only available part of the standard rig from 30 which motion can be imparted to the sand reel mechanism is the band wheel or its shaft. This has been generally recognized heretofore and attempts have been made with more or less success to so operate the 35 sand reel but all such arrangements have had certain inherent disadvantages recognized in the industry. For example, where the sand reel was driven by frictional contact with the periphery of the band wheel between the flights of the belt, the face of 40 the band wheel was soon rendered unfit for further service because of excessive wear on the friction generating periphery, so frequently a new band wheel had to be substituted because a continued use of the worn band wheel not only caused the band wheel to be out of round but it would also wear and tear the belt. Another disadvantage 45 encountered was that the pressure of the reel against the band wheel caused excessive wear of the band wheel bearings so that the band wheel soon got out of alignment requiring frequent rebabbing. Since the bull wheel is driven by the band wheel 50 it will be apparent that when the band wheel

got out of alignment the wear on the band wheel tug became excessive.

Another disadvantage of the above referred to frictional drive is that the loose bearings often caused loss of frictional contact between the band wheel and the sand reel when the bailer was being elevated. In such an event it was necessary to lower the bailer to the bottom of the well and again begin the elevating operation with no assurance that the next operation would be successful. This causes considerable loss of time, thereby increasing the operating cost of drilling the well.

In the prior constructions where the knuckle block tail post and swing lever were used the bearings soon became worn, causing loss of frictional contact with the reel so that it became dangerous to run in at high speeds, and the band wheel face and the face of the friction drum of the sand reel frequently became so hot that the effective frictional contact between the two was destroyed necessitating frequent shutdowns. Another objection has been that when the friction drum became hot and then suddenly contracted, it would burst endangering the lives of the crew.

The above disadvantages have long been known, but in so far as we are aware, prior to our invention, no adequate means has been provided to overcome them. Our invention contemplates the provision of means whereby the sand reel may be operated by a direct drive from the band wheel shaft and the mechanism may be so constructed that the sand spool may be positioned in front of the rig on the "walk" side with the reel in alignment with the sand sheave placed at the top of the derrick, so that there will be a straight pull exerted on the sand line permitting the line to properly spool upon the reel without liability of the line piling up upon one end and falling off of the reel and chafing on the flange with attendant disadvantages which would happen where the reel was offset with respect to the center of the sand sheave.

The desirability of providing a direct pull on the sand line has always been appreciated, but except for the examples above given, it has generally been considered impossible to so conduct the drive mechanism for the sand reel on account of the peculiar construction of the rig.

The rig consists essentially of a main center sill, transverse mud sills, subsill on the mud sills parallel with the diagonal main line on the main sill, jack posts, one on the main sill and one on subsill, sampson post on main sill, beam on sampson post derrick, band wheel on the jack posts, bull wheel and appurtenances as is well understood.

- 10 The problem then is to drive the sand reel by a direct drive from the band wheel shaft so that there will be a direct pull from the sand sheave and to so locate the spool and its drive mechanism as to not interfere 15 with the operating mechanism of the rig.

With such a mechanism means should be provided whereby a sensitive slip clutch may be included between the shaft and the spool for the following reasons. Sometimes the 20 bailer becomes caught in the hole, or it may be covered up with cavings, so if no means were provided to allow some part of the mechanism to slip the cable would part necessitating a difficult fishing job which 25 often results in a plugged hole. Another reason for the slip clutch is that the driller's art of feeling for the bottom of the hole can be sensitively practiced due to the facility and ease of the pick up. That is the 30 case of manipulating the bailer at the bottom of the hole.

The generic features of our invention as well as the novel details of construction of the illustrated embodiment thereof will be 35 apparent by reference to the following description in connection with the accompanying drawings in which:

Figure 1 is a plan view of a standard rig to which our invention is applied.

40 Figure 2 is a diagram of the standard rig. Figure 3 is a perspective view of the sand reel operating mechanism.

Figure 4 is a sectional view on the line 4-4 of Figure 3.

45 Figure 5 is a sectional view on the line 5-5 of Figure 7.

Figure 6 is a sectional view on the line 6-6 of Fig. 4, and

50 Figure 7 is a top plan view of the sand reel.

The standard rig as shown consists of the derrick and the main foundation and of course, per se forms no part of our invention.

55 The main sill A of the main foundation is connected to the derrick B in the usual way. The jack posts C and D support the band wheel shaft E of the band wheel F by means of which the moving parts of the rig

60 are driven, the band wheel receiving its motion from the usual belt driven by the engine. The band wheel shaft is at right angles to the main line G and the subline H, these lines being diagonal to the longitudinal center of the main sill A so as to allow

for the front jack post D and to permit the longitudinal center of the walking beam I to align with the main line, G, whereby the walking beam may operate without striking the front jack post D. J is the sand line 70 sheave.

The distance from the outside of the front jack post D to the band wheel of a standard drill rig is approximately thirty inches. The jack post box is fourteen inches wide, the set collar is two and one half inches and the band wheel flange projects one inch beyond the face of the band wheel, so there are only thirteen and one half inches on the front end of the band wheel shaft (that is, 75 between the band wheel and the jack post D) within which to construct a clutch drive by means of which the power may be taken off the band wheel shaft to operate the sand reel but by embodying our invention, the 80 drive may be effected. This can be accomplished in the following manner. At the upper ends of the jack posts C and D are bearings 3 and 4, in which is mounted the band wheel shaft E driven by the engine 85 through the band wheel F. A clutch 7 is keyed to the shaft E and is bolted rigid with the wheel F through the medium of the bolts 8 which pass through the web of the drum through the wheel F and through a 90 collar 9, also keyed to the shaft, as will be clearly seen by reference to Fig. 6.

A sliding clutch collar 10 is mounted on the shaft E and it is provided with grooves 11 and 12. In the groove 11 are the arms of a yoke 13 on the end of a lever 14, pivoted to the bracket 15 rigid with the sprocket 16, loosely mounted on shaft E, the diameter of the sprocket being greater than that of the drum 7. The groove 12 receives the pins 17 and 18 of a clutch shifter yoke 19 which is operated by the rod 20 mounted in the bracket 21 carried by the standard 2 (see Fig. 3). Therefore, when the rod is turned, the collar 10 will be shifted to rock the lever 14.

On the upper end of the lever 14 is a link 22 which causes a clutch band 23 mounted about the drum 7 to expand and contract so as to engage and disengage the periphery 115 of the clutch drum. The link 16 extends through the sprocket, as seen in Fig. 6. When the band 23 binds on the periphery of the clutch drum, it will rotate with the clutch drum. Therefore, the sprocket 16 will be rotated but when the band is released from the clutch drum, the wheel 6, shaft 5 and clutch drum may rotate without rotating the sprocket.

The sprocket 16 is preferably made in 120 halves and the two halves are connected at 24 (see Fig. 4) so that the sprocket can be removed from the shaft for the purpose of inspection and repairs without taking off the shaft 5.

The sprocket 16 drives a sprocket 25 through the medium of a chain 26. The sprocket 25 is rigid with the collar or hub 27 of a disk 28, loosely mounted on a shaft 29, supported in bearings 30 and 31 in the pillow blocks 32 and 33, the pillow blocks being in turn supported upon the portable skids or runners 34 and 35. Since the disk 28, the hub 27 and the sprocket 25 are rigidly connected, it will be apparent that these may rotate on the shaft 29 without rotating the shaft and since the sand reel 36 is keyed to the shaft, the sand reel will be rotated only when the shaft rotates.

15 Interposed between the ends of the sand reel and the disk 28 is a drum 37, keyed to the shaft 29 and provided with two circumferential clutch faces 38 and 39, divided by an annular partition 40 (see Fig. 5). About 20 the clutch face 38 is a friction band 41, to one end of which is connected a link 42 fastened to one arm of an elbow lever 43, pivoted at 44 to a plate 45, the plate being adjusted for wear by the hinged take up 25 bolt 46, fastened to another plate 47 on the band. The other arm of the elbow lever between the ends of the band is fastened to a link 46', connected to the upper end of the lever 47' pivoted at 48 to the bracket 30 49 rigid with the disk 28. The lower end of the lever 47' is bifurcated to form a yoke-shaped end 50, engaging the ends of the fingers or bars 51 and 52 carried by the head 53 on the sleeve 54, loosely mounted on the 35 shaft 29. The fingers or bars 51 and 52 project through the sprocket 25 and they have longitudinal movement through openings therein.

When the sleeve 54 is shifted away from 40 the disk 28, the lower end of the lever 47' will be shifted away from the disk 28 and the upper end of the lever 47' will move toward the disk 28, shifting the link 46' in the same direction to swing the arm of the 45 elbow lever to which it is connected toward the sand reel. The other arm of the elbow lever will impart a longitudinal movement to the link 46 to open the band or expand it. Therefore, the sleeve 54, the sprocket, 50 the hub 27, the disk and the clutch band 41 may rotate about the axis of the shaft 29 without imparting a rotative movement to the drum 37. When the sleeve 54 is shifted in an opposite direction, however, the band 55 41 will be contracted about the clutch face 38 so that the drum 37 will rotate and since it is keyed to shaft 29, the shaft 29 will rotate, rotating the sand reel 36 which is also keyed to the shaft 29.

60 We have provided mechanism for shifting the collar or sleeve 54 and it consists of an elbow lever 55, pivoted in the bracket 56 bridging the space between the skids 34 and 35, as clearly seen in Figs. 3 and 7.

65 One arm of the elbow lever is provided with

a yoke 57, which engages a groove 58 in the collar 54. The other end of the elbow lever is connected to an actuating rod 59, which may have longitudinal movement imparted to it by an appropriate means so as to swing the lever 57 about its pivot point 60. The rod 59 is also connected to one end of a rocking lever 61, pivoted at 62, the end 63 of the lever 61 being connected to a link rod 64 which engages the pivotal point 65 of the toggle levers 66 and 67 (see Fig. 4).

The toggle lever 67 is pivoted to the base 68 of a bracket having an upstanding portion 69 to which an elbow lever 70 is pivoted, 80 one arm of the elbow lever being fastened to the upper end of the toggle 66. Therefore, when the rod 64 is moved longitudinally, the toggle levers will rock the elbow lever 70. The upper end of the elbow lever is pivotally fastened to a link bolt 71 connected to the end 72 of a brake band 73 mounted about the clutch face 39. The other end of the brake band 73 is connected to the lever 70 by a link bolt 73, as will be clearly seen by reference to Fig. 2.

The levers 55 and 61 are so connected to the rod 59 and bear such co-operating relation that when the rod 59 is shifted in one direction to cause the collar or sleeve 54 to move in a direction to contract the clutch band 41, the lever 61 will be effective in causing the brake band 73 to expand and when the collar 54 is shifted in an opposite direction so as to release the drum 37, the brake band 100 will contract about its face 39. So it will be seen that the bands 41 and 73 alternately expand and contract. The reason for this is that when the bailer is to be released into the well, the driving connection must not be functioning. The shaft 29 then can have a free turning movement retarded only by the brake band 73, which will be under the control of the rod 59. Therefore, the operator can control the speed of rotation of the sand reel 36 and consequently the speed of descent of the bailer, it being understood that the driving action through the sprocket 16, the sprocket chain and the sprocket 25 is such as to cause a cable winding motion to be imparted to the sand reel 36 whereas the brake band 73 is to retard the unwinding movement of the sand reel 36.

When the parts are assembled and the shaft 5 is turning, the operator can cause the sprocket 16 to rotate by operating the clutch band 23 to cause it to bind on the drum 7. This will cause the sprocket 25 to rotate as heretofore explained. Then the operator can shift the rod 59 so that the band 41 will bind on drum 37, causing the bailer cable to wind on reel 36, it being assumed that the bailer is in the well. During the time the bailer is being raised should the bailer strike an obstruction or hang on any

- projection, the clutch band 41 will slip about the face 38 of the drum 37, thereby eliminating the liability of plugging the hole with the bailer or leaving the bailer in the hole.
- 5 When the bailer has been drawn to the top of the well and it is desired to lower it again, the operator will manipulate the rod 59 to expand the band 41. This action automatically contracts the band 73 so that the 10 bailer can be lowered into the well but under the control of the operator who can manipulate the rod 59 so as to increase or decrease the amount of friction or resistance offered by the band to the face 39 of the drum 37.
- 15 When the bailer has been lowered to the bottom of the well, the rod 59 will again be shifted so as to release the brake band but throw in the clutch band 41, when the winding operation will begin again.
- 20 It will be apparent from the foregoing that the sand reel mechanism built in accordance with our invention, will eliminate the difficulties encountered in sand reel constructions as heretofore practiced, and among the 25 manifold advantages of our invention may be mentioned the fact that the band wheel will not become worn by the sand reel mechanism so it gives indefinite service. Less fuel will be required to operate the engine, 30 less strain on engine, no vibration will be communicated to the rig, and since the necessity for repairs and replacement will be reduced to a minimum, the operating expense will be materially reduced.
- 35 Attention is also directed to the fact that with the old style sand reel the reel could not be operated fast enough to keep up with small doses of water, thus necessitating short under-reaming jobs, whereas with our 40 invention, the bailing may be carried on more rapidly so that frequently, under-reaming is eliminated and by reason of the fact that there is a direct pull on the sand line at all times, perfect spooling will be insured.
- 45 The sand reel may be mounted on skids to render the same easily portable.
- What we claim and desire to secure by Letters Patent is:
- 50 1. In combination with a standard well drilling rig, including the usual derrick having a sheave at its top, front jack post, back jack post, band wheel shaft and band wheel, of a sand reel operating mechanism comprising a driven shaft, a sand reel spool on the driven shaft, in line with the sheave, a sand line on the spool passing through the sheave so that there will be a direct pull on the line at all times, driving connections between the band wheel shaft and the driven 55 60 65 70 75 80 85 90 95 100 105 110 115 115
- shaft, the driving connections including slip clutch means whereby the band wheel shaft may slip with respect to the spool.
2. In combination with a standard well drilling rig, including the usual derrick, having a sheave at its top, front jack post, back jack post, band wheel shaft and band wheel, of a sand reel operating mechanism comprising a driven shaft, a sand reel spool on the driven shaft, in line with the sheave, a sand reel line on the spool passing through the sheave so that there will be a direct pull on the line at all times, driving connections between the band wheel shaft and the driven shaft, the driving connections being located on the band wheel shaft between the front jack post and the band wheel, the driving connections including slip clutch means whereby the band wheel shaft may slip with respect to the spool.
3. In combination with a standard well drilling rig, including the usual derrick, having a sheave at its top, front jack post, back jack post, band wheel shaft and band wheel, of a sand reel operating mechanism comprising a driven shaft, a sand reel spool on the driven shaft, in line with the sheave, a sand reel line on the spool passing through the sheave so that there will be a direct pull on the spool, a sprocket loose on the band wheel shaft, a sprocket loose on the driven shaft, a chain connecting the sprockets, clutches for connecting the sprockets to the respective shafts, at least one of said clutches being of the friction type whereby the band wheel shaft may slip with respect to the driven shaft, and means for controlling the frictional engagement of the slip clutch.
4. In combination with a standard well drilling rig, including the usual derrick, having a sheave at its top, front jack post, back jack post, band wheel shaft and band wheel, of a sand reel operating mechanism comprising a driven shaft, a sand reel spool on the driven shaft, in line with the sheave, a sand reel line on the spool passing through the sheave so that there will be a direct pull on the spool, a sprocket loose on the band wheel shaft, a sprocket loose on the driven shaft, a chain connecting the sprockets, clutches for connecting the sprockets to the respective shafts, both of said clutches being of the friction type whereby the band wheel shaft may slip with respect to the driven shaft, and means for controlling the frictional engagement of the slip clutch.
- In testimony whereof we have hereunto set our hands.
- RICHARD W. SAGE.
HARRY R. BOUGHNER.
